United States Patent Office

Des. 212,350
Patented Oct. 8, 1968

212,350

COMBINED JUG AND DISPENSER

Norman A. Kelly, Wayne Township, Kosciusko County, Ind., assignor to Haskon, Inc., Warsaw, Ind., a corporation of Delaware

Filed Jan. 16, 1967, Ser. No. 5,446

Term of patent 14 years

(Cl. D9—52)

FIG. 1

FIG. 3

FIG. 2

FIG. 4

FIG. 5

FIG. 1 is a perspective view of a combined jug and dispenser embodying my new design;

FIG. 2 is a top plan view;

FIG. 3 is a side elevational view, the opposite side being a mirror image of the side shown;

FIG. 4 is a front elevational view; and

FIG. 5 is a rear elevational view thereof.

I claim:

The ornamental design for a combined jug and dispenser, as shown and described.
